[57] CLAIM

The ornamental design for a combined wet/dry hand-held vacuum cleaner, as shown and described.

DESCRIPTION

FIG. 1 is a perspective view of a wet/dry hand-held vacuum cleaner showing our new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The electric cord shown in FIGS. 1-6 is shown broken away for ease of illustration and is understood to represent indeterminate length.
